United States Patent Office

Des. 207,286

Patented Mar. 28, 1967

207,286

MICROWAVE OVEN

Robert I. Bruder, Shaker Heights, Ohio, assignor to Litton Precision Products, Inc., Palo Alto, Calif., a corporation of Delaware

Filed Aug. 25, 1966, Ser. No. 3,582

Term of patent 14 years

(Cl. D81—26)

Fig. 4

Fig. 5

Fig. 6

Fig. 7

FIGURE 1 is a perspective view of the preferred design of the microwave oven.

FIGURE 2 is a perspective view of an alternate design similar to the preferred design of the microwave oven.

FIGURE 3 is a top view of both the ovens of FIGURES 1 and 2.

FIGURE 4 is a right elevational side view of the microwave ovens of FIGURES 1 and 2.

FIGURE 5 is a left elevational side view of both the microwave ovens of FIGURES 1 and 2.

FIGURE 6 is a fragmentary detail of the recessed grill pattern disclosed on the door member in FIGS. 1 and 2. The grill pattern is understood to continue uniformly throughout said recessed area.

FIGURE 7 is a detail of the grill of the microwave ovens of FIGURES 1 and 2.

I claim:

The ornamental design for a microwave oven, as shown and described.
